United States Patent Office

Des. 178,018
Patented June 12, 1956

178,018

MICROPHONE

Burt E. Schell, Jr., Mundelein, Ill., assignor to Shure Brothers, Incorporated, Chicago, Ill., a corporation of Illinois

Application June 6, 1955, Serial No. 36,390

Term of patent 14 years

(Cl. D26—14)

Fig. 1.

Fig. 2.

Fig. 3.

Fig. 4.

Figure 1 is a perspective view of a microphone embodying my new design;

Fig. 2 is a side elevational view thereof;

Fig. 3 is a front elevational view thereof; and

Fig. 4 is a top plan view thereof.

The features of my design reside in those portions shown in full lines, the dotted line showing being mounting means for illustrative purposes only.

I claim:

The ornamental design for a microphone, substantially as shown and described.
